(57) **CLAIM**

The ornamental design for an endotracheal intubation device handle, as shown and described.

DESCRIPTION

FIG. 1 is a left side view of the endotracheal intubation device handle with environmental structures shown in broken lines.

FIG. 2 is a front view of the endotracheal intubation device handle.

FIG. 3 is a back view of the endotracheal intubation device handle.

FIG. 4 is a top view of the endotracheal intubation device handle.

FIG. 5 is a bottom view of the endotracheal intubation device handle; and,

FIG. 6 is a right side view of the endotracheal intubation device handle.

The broken lines showing environmental structures are for illustrative purposes only, and form no part of the claimed design.
